DESIGN FOR A BATHROOM SCALE

Clarence Karstadt, Glen Ellyn, Ill., assignor to Sears, Roebuck and Co., Chicago, Ill., a corporation of New York

Application September 21, 1939, Serial No. 87,330

Term of patent 3½ years

To all whom it may concern:

Be it known that I, Clarence Karstadt, a citizen of the United States, residing at Glen Ellyn, in the county of Du Page and State of Illinois, have invented a new, original, and ornamental Design for a Bathroom Scale, of which the following is a specification, reference being had to the accompanying drawing, forming a part thereof.

Fig. 1 of the drawing is a top plan view of a bathroom scale embodying my new design.

Fig. 2 is a front view thereof.

Fig. 3 is a side view of the same.

I claim:

The ornamental design for a bathroom scale,
as shown.

CLARENCE KARSTADT.
